CLAIM

The ornamental design for a combined light assembly and reflex measuring tool, as shown and described.

DESCRIPTION

FIG. 1 is a perspective view showing the top right and front of a light assembly and reflex measuring tool for connection to a stethoscope;

FIG. 2 is a perspective view showing the bottom right and rear thereof;

FIG. 3 is a top plan view thereof;

FIG. 4 is a right side elevational view thereof;

FIG. 5 is a front elevational view thereof;

FIG. 6 is a rear elevational view thereof;

FIG. 7 is an exploded view thereof; and,

FIG. 8 is an exploded view thereof.

The broken line showing of the stethoscope is for illustrated purposes only and forms no part of the claim design.
